C. H. SMITH

STOVE

Filed June 30, 1923

INVENTOR

Clifford H. Smith
John A. Deismith

BY

ATTORNEY

UNITED STATES PATENT OFFICE.

CLIFFORD H. SMITH, OF SAN JOSE, CALIFORNIA.

STOVE.

Application filed June 30, 1923. Serial No. 648,762.

To all whom it may concern:

Be it known that I, CLIFFORD H. SMITH, a citizen of the United States, and resident of San Jose, in the county of Santa Clara and State of California, have invented certain new and useful Improvements in Stoves, of which the following is a specification.

My invention relates particularly to a food receptacle heated by the exhaust from an internal combustion engine.

It is one object of my invention to provide a device of the character indicated so constructed as to permit the passage of the exhaust gases from an engine therethrough.

It is another object of my invention to provide a device of the character indicated provided with means for controlling the passage of said exhaust through said receptacle.

It is still another object of my invention to provide a means for preventing injury to the receptacle if the pressure exerted by the exhaust rises unduly above normal.

25 In the drawing;—

Figure 1 is a plan view of the device, parts being broken away.

Figure 2 is a section on line 2—2 of Figure 1.

30 Figure 3 is a section on line 3—3 of Figure 1.

Figure 4 is an enlarged sectional detail of the exhaust control.

Figure 5 is an enlarged detail of the corner construction of the device.

Referring more particularly to the drawing, 1 indicates the running board of an automobile and 2 the exhaust pipe from the engine not shown.

40 At 3 I show a case having inner and outer walls 4 and 5 between which is arranged a heat insulating medium 6. The case is provided with a door at one end as at 7 hinged at 8 and secured by catch 9 and mounted on running board 1 by brackets 9^a. At 10 is shown a food receptacle securely fastened to the top case 3 by rivets 11, spaced from the sides, rear end and bottom of the case to form an encompassing space 12, and 45 rigidly held in position by braces 13 se-

cured thereto and to case 3 as shown. The front end of receptacle 10 is provided with a flange 14 engaging the front of case 3 around the front opening therein so that free access may be had to the receptacle 10 when door 55 7 is opened.

At 15 is shown an orifice in one side of case 3 near the bottom and one end thereof through which space 12 communicates with the atmosphere. Diagonally opposite to orifice 15 is another orifice 16 communicating with exhaust pipe 2 by means of a pipe 17. The opening between pipes 2 and 17 is normally closed by a gate valve 18 hinged as at 19 and provided with an arm 20 operated in any suitable manner as by a rod 21 whereby the valve may be opened and closed at will. The valve 18 is preferably mounted so that when in a normal position the exhaust is closed off from pipe 17 but has 55 a free passage through pipe 2, and when operated to the position indicated in dotted lines at 22 the exhaust is closed off in pipe 2 but has a free passage through pipe 17.

At 23 I show a door hinged at 24 in the side of case 3 and under normal gas pressure held in a closed position by means of a spring 25 engaging the outer surface thereof and a bracket 26 mounted on the bottom of running board 1. If the engine should 60 back-fire while the exhaust is passing through pipe 17 the abnormal pressure will force door 23 open and so permit the gas to escape easily instead of possibly blowing the case 3 apart.

When in use beverages and foods to be served hot are placed in the receptacle 10, the door 7 closed and the valve 18 opened to position 22 so that the exhaust from the running engine will be passed through pipe 17 and around receptacle 10 filling space 12 and finally discharging at 15. In this manner beverages and foods may be subjected to any desired degree of heat within the range of the exhaust gases by controlling its 65 flow into pipe 17, and for any desired length of time.

It is to be understood of course, that while I have herein shown and described but one specific embodiment of my invention, changes 70

in form, construction and method of operation may be made within the scope of the appended claim.

I claim:—

5 In combination with a case, a receptacle arranged therein and closed off therefrom and spaced a distance therefrom, a door common to said case and receptacle, a door mounted on said case, resilient means for

normally holding said door in a closed position said case having inlet and discharge openings formed therein communicating with said space, an internal combustion engine exhaust pipe, and a tube communicating with said inlet opening and said exhaust pipe. 10 15

CLIFFORD H. SMITH
